REFRIGERATOR CAR CONSTRUCTION

Charles D. Bonsall, Chicago, Ill., assignor to
Standard Railway Devices Company, a corpora-
tion of Delaware

Application May 14, 1941, Serial No. 393,332

3 Claims. (Cl. 62—17)

This invention relates to refrigerator cars used to transport perishable commodities at a predetermined temperature. The usual features of a refrigerator car are an insulated body to prevent or retard ingress of heat during warm weather and egress of heat during cold weather, and a cooling means and a heating means to be used during warm and cold weather respectively.

This invention applies particularly to cars in which the cooling means, preferably containers for water ice, eutectic ice, brine or dry ice, are disposed immediately below the roof of the car. The lading is supported in spaced relation to the floor by a foraminous rack. Flues, preferably associated with the side walls of the car, communicate between the cooling means and the space under the floor rack to provide a path for the circulation of air. The path is from the cooling means downwardly through the aforementioned flues, through the space under the floor rack, upwardly through the lading compartment thereby cooling the lading, and finally to the cooling means from where the cycle is repeated.

An object of the invention is to provide for more effective and more efficient cooling of the car by making possible more complete contact between the refrigerant and the circulating air. I have disclosed a form of refrigerant container adapted to bring about more effective and more efficient refrigeration which embodies the following features:

The bottom of the container is foraminous, preferably made of expanded metal, wire netting or perforated metallic sheet. Tests which have been made indicate that a refrigerant container having a foraminous bottom cools the circulating air at a very considerably faster rate and also imparts a somewhat lower temperature to such circulating air.

The walls of the tank are inclined; that is, they diverge downwardly so that the tendency, when the ice adjacent the foraminous bottom melts, is for the downwardly diverging walls to permit the remaining ice to settle closer to the bottom of the container. The circulating air will then be more efficiently cooled than if the refrigerant is disposed near the top of the container.

The side, and preferably the end, walls of the container are imperforate. In the first place, I wish to prevent the ice from clinging to the side walls of the container; when ice comprised of a plurality of relatively small pieces is partially melted, such pieces become frozen together into a solid mass and if the side walls of the container are formed so as to permit such ice to cling there-

to, the ice forms a bridge between the walls and above the bottom of the container. The refrigerant is thereby removed from the path of air circulation with a consequent loss of refrigerating efficiency. In the second place, the imperforate walls make it necessary for the circulating air to flow between the container bottom and the drip pan. Where foraminous walls are provided, it is possible for the air to circulate through and above the container; when the ice is partially melted, there is a large space within the container available for air circulation so that it is probable that parts of the air flowing through the container do not come in contact with the refrigerant. By forcing all the circulating air through the relatively narrow duct below the container, I make certain that every part of the air comes in intimate contact with the refrigerant.

Other objects and advantages of my invention will be apparent from the following detailed description by referring to the accompanying drawings.

In the drawings:

Fig. 1 is a transverse section through a refrigerator car embodying my invention.

Fig. 2 is a plan view of the refrigerant container shown in Fig. 1, having a portion of the top broken away.

Figs. 3 and 4 are transverse sections through refrigerant containers showing modified forms of my invention.

Fig. 5 is an enlarged view of the portion of Fig. 2 enclosed within the circle.

Fig. 6 is a section on line 6—6 of Fig. 5.

Fig. 7 shows another modification of my invention.

The general parts of the refrigerator car shown in Fig. 1 are insulated roof A; side walls B; floor D; refrigerant containers E; hatch F for loading refrigerant into one of the containers E; side wall flues G; foraminous floor rack H and space J between the rack H and the floor D. A refrigerant container E is preferably positioned directly below the roof A and adjacent each side wall B. A drip pan K is provided below each container E and a partition L is disposed in an upstanding position at the edge of the drip pan K. The drip pan K and the partition L cooperate with the roof A and the upper part of the side wall B to form an enclosure M around the container E, an air inlet opening N to the enclosure M being provided by spacing the partition L from the roof A. An air discharge opening P leads from the enclosure M to the flue G at a lower elevation than the air

inlet opening N. Cars of this type commonly have a row of refrigerant containers E near each side wall B, which containers are spaced apart at the center of the car. The partitions L are also spaced apart to form a duct Q which communicates between the lading compartment R and openings N.

Air circulation is as follows: Air in the lading compartment R is warmed by contact with the lading and rises through the duct Q to enter the enclosing structures M through the air inlet openings N. The air is then cooled by contact with the cold refrigerant containers E and falls by reason of its lower temperature and therefore greater density through the discharge openings P and flues G to the space J whence it rises through the rack H to the lading compartment R. The above described cycle is thereafter continuously repeated.

The container 2 shown in Figs. 1 and 2 is comprised of an upper part 3 and a lower part 5 which are secured together, preferably by a removable means, such as the bolts 6 shown.

The lower part 5 is comprised of imperforate side walls 8, preferably imperforate end walls 9 and a foraminous bottom 10. Longitudinally extending angle shaped stiffeners 11 are secured to and form a part of the container 2 and are disposed at the juncture of the side walls 8 and bottom 10. Vertical stiffeners 13 are secured to an upstand from the longitudinal stiffeners 11 and substantially horizontal stiffeners 14 disposed below the bottom 10 extend between and are secured to the longitudinal stiffeners 11. The lower margins of side walls 8 are flanged (16) into the container above the longitudinal stiffeners 11. The bottom 10 of the container, which bottom may be expanded metal, wire screen, perforated plate or other foraminous material, rests upon the horizontal stiffeners 14 and its margins 17 underlie the inwardly directed flanges 16 of the side walls 8.

The upper part 3 of the container 2 is preferably comprised of imperforate side (20) and end (21) walls and a top 23 which is preferably imperforate except for an opening 24 aligned with the hatch F in the roof A for loading refrigerant into the container. The top 23 of the container may be provided with stiffening corrugations 25. Carlines 26 extend between and are secured to the opposite side walls A of the car and the container E is supported by brackets 27 secured to the ends of the longitudinal stiffeners 11 and to the carlines 26.

Warm air from the lading compartment R, as hereinabove explained, rises through the duct Q between the partitions L and then flows downwardly through the passage 34 between the container E and the respective partition L and through the duct 35 between the container bottom 10 and the drip pan K. The container side wall 36 adjacent the partition L is comprised of upper (20) and lower (8) parts and is substantially imperforate; practically the entire amount of circulating air is thus forced to flow through the relatively narrow duct 35 where it is assured of having intimate contact with the refrigerant within the container E. In cases where the side walls of the container are foraminous, some of the air flows through such foraminous walls into the interior of the container; then when a considerable part of the refrigerant has melted, a large open space is available for air flow so it is doubtful if all of the air comes in contact with the refrigerant. Obviously, if

some of the circulating air flows through the refrigerant chamber M without being cooled, the temperature in the car cannot be as low as if the air is uniformly cooled. Furthermore, the smooth surfaces of the imperforate side walls 8, 20 make it more probable that the refrigerant will fall to the bottom of the container as the refrigerant adjacent the bottom melts; whereas, if the side walls were rough, there would be a tendency for the refrigeration to cling thereto.

Fig. 3 shows a refrigerant container 40 somewhat similar to that shown in Figs. 1 and 2, but also embodies side walls 41, 43 which diverge toward the bottom 44 of the container 40. This is to prevent refrigerant becoming wedged between the side walls 41, 43 and facilitates the dropping thereof onto the bottom 44 of the container when the refrigerant adjacent the bottom melts.

Fig. 4 shows a refrigerant container 50 constructed in one piece and comprising longitudinally extending angle shaped stiffeners 51 to which substantially vertical side walls 53 of the container are secured. Vertical stiffeners 54 are preferably secured to the longitudinal stiffeners 51 and to the side walls 53 of the container. Substantially horizontal stiffeners 56 which consist of angles with their end portions flattened extend between the longitudinal stiffeners 51. The bottom 57 of the container 50 is preferably made of foraminous material, such as the expanded metal shown, and is riveted to the longitudinal stiffeners 51. The substantially horizontal stiffeners 56 are secured to the longitudinal stiffeners 51 by some of the rivets 59 which secure the bottom 57 of the container to the longitudinal stiffeners 51. Upstanding members 60 are riveted to the upper parts of the side walls 53 and support the container top 62, which is preferably foraminous.

Figs. 5 and 6 illustrate in detail a method of securing the expanded metal bottom 10 to the stiffeners 14 which underlie such bottom. This securing means comprises a bolt 65 which extends through a hole 68 in the expanded metal, the head 66 of which bolt overlies parts of the expanded metal adjacent the hole.

In the modification shown in Fig. 7, the lower part 75 of the container 76 is comprised of longitudinally extending angle shaped stiffeners 78 connected by transversely extending stiffeners 79 and having upstanding, substantially vertical stiffeners 81 secured thereto. The side walls of the lower part 75 are formed of substantially imperforate plates 82 secured to the stiffeners 78, 81 and formed with outwardly projecting flanges 84 on the upper margins thereof. The bottom 85 of the container may be formed of any of the foraminous materials hereinabove mentioned. The upper part 88 of the container includes the longitudinally extending stiffeners 89 and the inverted U-shape stiffeners 91 secured at their opposite ends to the longitudinal stiffeners 89. Foraminous material 92 is secured to the stiffeners 89, 91 and the upper part 88 is attached to the lower part 75, preferably by a removable means, such as the bolts 94 shown.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car, a wall structure ar-

ranged to form a car wall and a flue, a refrigerant container adjacent said wall, said container having a bottom and spaced apart walls and means cooperating with said bottom to form a duct communicating with said flue, opposite walls of said container comprising substantially imperforate material formed with inwardly projecting lower marginal flanges, a plurality of spaced apart stiffeners for said bottom extending between said last mentioned walls, said bottom comprising foraminous material arranged with its margins interposed between said flanges and said stiffeners.

2. In a refrigerator car having a wall structure arranged to form a car wall and a flue; a refrigerant container adjacent said wall, said container having a bottom and spaced apart walls and means cooperating with said bottom to form a duct communicating with said flue, opposite walls of said container constructed of substantially imperforate material, and stiffeners extending transversely of said container and arranged to support said bottom, said bottom constructed of substantially flat foraminous material.

3. In a refrigerator car having a wall structure arranged to form a car wall and a flue; a refrigerant container for solid refrigerant adjacent said wall, said container having a bottom and spaced apart walls and means cooperating with said bottom to form a duct communicating with said flue, stiffeners extending transversely of said container and arranged to support said bottom, said walls of said container constructed of substantially imperforate material and arranged to diverge downwardly thereby facilitating movement of the refrigerant toward the bottom of the container and said bottom constructed of substantially flat foraminous material.

4. In a refrigerator car having a wall structure arranged to form a car wall and a flue; a refrigerant container adjacent said wall, said container having a bottom and spaced apart walls, stiffeners extending longitudinally of said container and having lower flanges, means cooperating with said bottom to form a duct communicating with said flue, opposite walls of said container constructed of substantially imperforate material formed with lower marginal flanges substantially abutting said stiffener flanges, stiffeners extending transversely of said container and arranged to support said bottom,

said bottom constructed of substantially flat foraminous material.

5. In a refrigerator car having a wall structure arranged to form a car wall and a flue; a refrigerant container adjacent said wall, said container having a foraminous bottom and spaced apart walls and means cooperating with said bottom to form a duct communicating with said flue, opposite walls of said container arranged to diverge downwardly thereby facilitating movement of the refrigerant toward the bottom of the container, and stiffeners extending transversely of said container and arranged to support said bottom.
- 10 6. In a refrigerator car having a wall structure arranged to form a car wall and a flue; a refrigerant container adjacent said wall, said container having a bottom and spaced apart walls and means cooperating with said bottom to form a duct communicating with said flue, said walls of said container constructed of substantially imperforate material, and stiffeners extending transversely of said container and arranged to support said bottom, said bottom having a plurality of apertures therein distributed throughout substantially the entire area of said bottom, the aggregate area of said apertures comprising the major portion of the area of said bottom.
- 15 7. In a refrigerator car having spaced apart carlines and a wall structure arranged to form a car wall and a flue; a refrigerant container adjacent said wall, said container having a bottom and spaced apart walls and means cooperating with said bottom to form a duct communicating with said flue, stiffeners for supporting said bottom extending longitudinally thereof beyond the ends of said container, means securing said stiffeners to said carlines, and said
- 20 8. In a refrigerator car having a refrigerant container adjacent the roof thereof, and a drip pan below said container and spaced therefrom to provide for air circulation therebetween, said container having imperforate side and end walls, a foraminous bottom, and a foraminous top.
- 25 9. In a refrigerator car having a refrigerant container adjacent the roof thereof, and a drip pan below said container and spaced therefrom to provide for air circulation therebetween, said container having imperforate side and end walls, a foraminous bottom, and a foraminous top.
- 30 10. In a refrigerator car having a refrigerant container adjacent the roof thereof, and a drip pan below said container and spaced therefrom to provide for air circulation therebetween, said container having imperforate side and end walls, a foraminous bottom, and a foraminous top.
- 35 11. In a refrigerator car having a refrigerant container adjacent the roof thereof, and a drip pan below said container and spaced therefrom to provide for air circulation therebetween, said container having imperforate side and end walls, a foraminous bottom, and a foraminous top.
- 40 12. In a refrigerator car having a refrigerant container adjacent the roof thereof, and a drip pan below said container and spaced therefrom to provide for air circulation therebetween, said container having imperforate side and end walls, a foraminous bottom, and a foraminous top.
- 45 13. In a refrigerator car having a refrigerant container adjacent the roof thereof, and a drip pan below said container and spaced therefrom to provide for air circulation therebetween, said container having imperforate side and end walls, a foraminous bottom, and a foraminous top.
- 50 14. In a refrigerator car having a refrigerant container adjacent the roof thereof, and a drip pan below said container and spaced therefrom to provide for air circulation therebetween, said container having imperforate side and end walls, a foraminous bottom, and a foraminous top.

CHARLES D. BONSALL.
